Patented Apr. 12, 1927.

1,623,994

UNITED STATES PATENT OFFICE.

SAMUEL BUCHSBAUM AND HERBERT BUCHSBAUM, OF CHICAGO, ILLINOIS.

VANITY BOX.

Application filed July 30, 1923. Serial No. 654,607.

Our invention relates to receptacles and more particularly to vanity boxes.

It is the purpose of our invention to provide a vanity box or receptacle for powder and a powder puff or similar toilet preparations and articles, which is simple in construction, compact in arrangement and neat in appearance.

It is particularly the purpose of the invention to provide such a receptacle that can be supported on a band or strap so that the same can be worn on the wrist.

It is more particularly a purpose of the invention to provide a device of the above mentioned character which has a hinged cover and which is provided with a mirror in which the hinge construction is simple and in which simple means is used for securing the straps to the box, and also, a simple construction is provided for holding the mirror in place in the container. The construction of the box and hinged cover and the mirror holding means are preferably such that the same can be easily and cheaply assembled.

Other objects and advantages of the invention will appear as the description of the accompanying drawings proceeds. However, we desire to have it distinctly understood that we do not intend to limit ourselves to the exact details shown and described, but that we intend to include as part of our invention all such obvious changes and modifications of parts as would occur to a person skilled in this art and as would fall within the scope of the claim.

In the drawings:

Fig. 1 is an enlarged longitudinal vertical sectional view of our improved vanity box, showing the hinged cover thereof open;

Fig. 2 is an enlarged fragmentary sectional view taken on a line 2-2 of Fig. 1;

Fig. 3 is an enlarged fragmentary sectional view of the device taken on a line 3-3 of Fig. 1; and

Fig. 4 is a fragmentary enlarged sectional view taken on a line 4-4 of Fig. 1.

Referring in detail to the drawings, our improved vanity box comprises a main body portion having a bottom 5 and upstanding side walls 6 and upstanding end walls 7. The end walls 7 are provided with openings 8 into which the strap attaching members 9 may be inserted. Said strap attaching members 9 are provided with elongated eyes 10 for receiving the loops 11 and 12 on the ends

of the strap 13. Said attaching members are punched out of a piece of sheet metal and comprise a cross bar 14 forming part of the loop and end connecting members 15 joining said cross bar with the main body portion 16 of said member. The main body portion is provided with a curved inner edge portion 17 and with laterally projecting portions 18 which are adapted to engage with the inner faces of the end members 7 to hold the members 9 in place therein. The openings 8 are in the form of elongated slots substantially the same length as the bar 14 so that the member 9 can be inserted from the inside through the slot and pushed outwardly until the projections or lugs 18 engage with the inner faces of the end walls 7.

Each of the side walls 6 is provided with an inwardly struck projection 19, said projections 19 being opposite each other to form a pair of opposite inwardly extending lugs. Said lugs are adapted to enter recesses 20 which are formed by striking the metal of the side flanges 21 of the cover member 22 inwardly, as clearly shown in Fig. 4. The inward striking of said flanges to form the recesses 20 provides inwardly struck lugs 23 opposite the recesses 20. It will be seen that when the cover member 22 is forced down on the main body portion 5, the springiness of the side members 21 will allow the same to be forced inwardly slightly upon engagement with the lugs 19 until the recesses 20 are opposite the lugs 19 when said lugs will enter said recesses snapping into place and thus hinging the cover to the main body portion of the box. Lugs 23', similar to the lugs 23, are also struck inwardly on the cover 22 in opposite pairs, thus providing a pair of lugs comprising a lug 23 and a lug 23', on each depending side flange 21 of the cover 22. Said lugs 23 and 23', serve to hold the mirror 24 in position. Said mirror is inserted by pressing the same downwardly against the top of the lid 22 past the lugs 23 and 23', the yieldability of the flanges 21 permitting this. The four lugs 23 and 23' will then hold the mirror 24 firmly in position. The side members 6 of the main body portion are also provided with inwardly struck lugs 25 which are adapted to enter the openings 26 on the side flanges 21 of the cover to hold the cover in closed position, as will be evident from Figs. 2 and 3. The cover is also provided with a downwardly extending flange 27 at the free end thereof

which is adapted to enter the main body portion of the box on the inside of the end member 7 opposite that at which the cover is hinged, and said flange member is slotted 5 and a portion thereof is left in position extending in alignment with the top of the cover 22 to provide a finger piece 28, as will be clear from Fig. 1. The cover 22 is also provided with a downwardly extending 10 flange 29 at the hinged end thereof, the corner 30 at the flange 29 being located at such a distance from the pivots 23 that the same will bind slightly against the end walls 7 adjacent thereto to hold the hinged cover in 15 an open position after the same has passed a predetermined angle relative to the body portion 5.

The container is shown as having a cake of powder 31 mounted on a metallic base 32 20 positioned in the bottom thereof and it will be noted that the members 9 are of such a size that the same will engage with the metallic backing 32 of the powder cake 31 to

aid in holding the same in position in the bottom of the box, altho such engagement 25 is not sufficient to prevent removal of the powder and metallic backing and substitution of other powder therefor. The container may also receive a powder puff or similar article 33 if desired.

Having thus described our invention what we desire to claim and secure by United States Letters Patent is:

In a receptacle, a body portion, a flanged cover hinged thereto, a mirror, and means 35 for securing said mirror in said lid, comprising opposite pairs of instruck lugs on the flanges of said cover, one pair of said lugs forming recesses for the reception of lugs on said body portion to hinge the cover 40 thereto.

In witness whereof, we hereunto subscribe our names this 6th day of July, A. D., 1923.

SAMUEL BUCHSBAUM.
HERBERT BUCHSBAUM.
